UNITED STATES PATENT OFFICE.

JOHN J. WILKINSON AND MICHAEL A. WILKINSON, OF OWEGO, NEW YORK.

CHAIR.

Application filed October 8, 1927. Serial No. 224,904.

Our invention relates generally to chairs and particularly to a folding chair, and has for its primary object the provision of a folding construction that economizes the greatest possible amount of space required and a minimum number of parts.

Another object is to provide a folding chair which despite its limited number of parts affords a solid substantial chair when 10 unfolded.

Still another object is to provide a folding chair in which the back and rear legs are of a single rigid unit and in which the foldable front legs and seat are so arranged 15 as to eliminate the necessity for extraneous and unsightly braces and cross leg supports.

One of the distinct advantages of our improved chair construction lies in the fact 20 that the chair when unfolded and ready for use simulates to a marked degree the appearance of the ordinary nonfolding chair and for this reason finds utility and use under circumstances not heretofore desirable with the ordinary type of folding chair.

Other objects and advantages will be apparent as the description proceeds, reference now being had to the figures of the 30 drawing wherein like reference numerals indicate like parts.

In the drawing:—

Figure 1 is a perspective view of our improved chair in unfolded position.

Figure 2 is a perspective view of the 35 chair in unfolded position as it appears from the rear.

Figure 3 is a perspective view of the chair in its folded or collapsed position.

Figure 4 is a detail illustrating the seat 40 pivot.

The reference numerals 1 and 2 refer to the side members of the frame which provides the rigid unit comprising the rear 45 legs and back of the chair. The upper cross piece 3 and the lower cross piece 4, between which is mounted the vertical back strip 5 complete this frame. The portions 6 and 7 of the side members 1 and 2 provide the rear legs of the chair, and cross pieces 3 and 4 and vertical piece 5, together with the upper ends of the side members 1 and 2 provide the chair back. This structure is similar to that commonly used in the 55 making of nonfolding chairs, and provides

a very substantial and solid frame work for the chair.

This frame, as well as the other parts of the chair to be described, may be, as shown in the drawings, constructed of wood, each 60 part thereof being formed separate and suitably secured together in the desired manner. It should be noted however that instead of making these parts of wood and fitting them together, the entire frame consisting of the side members 1 and 2, cross pieces 3 and 4 and vertical back member 5 may be stamped as a single piece from metal and formed with the desired curve. We do not limit ourselves therefore to the 65 wooden construction herein shown and described but wish it understood that a metal frame clearly falls with the scope of our invention.

Extending across between the side members 1 and 2 at a suitable height from the lower end of the rear legs 6 and 7, is a rod 8, the pivot for the seat 9. The rear edge of the seat 9 is provided with projecting ears 10 through which the rod 8 passes and 70 by means of which the seat may be pivoted on said rod 8. Located on the rod 8 between the ears 10 and the side members 1 and 2 are flanged washers 11, serving to 75 space the seat from such side members so as to prevent interference between the seat and side members when the seat is folded as shown in Figure 3. It will be observed 80 with reference to Figure 3 that due to the curve on which the chair back is formed 85 and the thickness of the frame members 1 and 2, the seat 9 when in folded position lies entirely within the planes defined by the edges of such frame members. The thickness of the chair when folded is therefore 90 no greater than the thickness of the 95 side members 1 and 2.

Secured to the inner surfaces of the side members 1 and 2 at points spaced suitably 100 above the pivot 8 of the seat 9, are headed pins 12 engaging within the longitudinal slots 13 formed in the upper ends of the front legs 15 and 16 of the chair. These legs 15 and 16 are preferably of metal although they may be made of wood or other 105 suitable material, and are provided at their lower ends with the bent portions 17 to provide feet for these legs and prevent scratching the floor or other surface upon which the chair may be set. It will be 110

noted that by bending the ends 17 inwardly, interference of these feet with the rear legs 6 and 7 when the chair is folded is avoided. The legs 15 and 16 are connected at a point 5 below the lower ends of the slots 13 by means of a rod 18 passing directly beneath the seat 9 and bent at its ends as at 19 to conform to the structure of said seat and to facilitate stacking the chairs when folded. 10 Strap members 20 are provided on the under surface of the seat 9 at each side thereof to provide bearings through which the ends of the rod 18 pass and upon which the seat is pivoted. 15 This rod 18 in addition to providing a support for the underside of the projecting seat 9, provides a connecting brace between the front legs 15 and 16. A second brace rod 21 connects the front legs further down 20 and lends rigidity of the structure. As shown in dotted lines in Figure 1, the front legs 15 and 16 may, if desired, be further connected by the strip 22, preferably integral with the legs and curved upwardly 25 slightly out of contact with the supporting surface. This would of course also add to the stability of the chair as well as permit the legs 15 and 16 to be formed from a single strip of material.

From the foregoing, it will be obvious 30 that by lifting up the outer end of the seat 9, the seat may be turned on its pivot 8 and as the seat is moved to the closed position adjacent the back member 5, the front leg members 15 and 16 will be carried therewith, sliding upwardly by virtue of the pin and slot connections 12 and 13, and, by virtue of the pivotal connection 20 with the underside of the seat 9, will assume a horizontal position directly inside the frame members 1 and 2 and lying entirely within the planes of said frame. 35

Likewise, upon lowering the seat 9 from folded position to open position, the connection with the rod 18 on the seat will cause the legs 15 and 16 to be carried outwardly and, due to the pin and slot connection 12 and 13, downwardly to engagement with the floor for supporting the chair. 40

Obviously from our construction, a considerable number of these chairs may be folded up and stored away, requiring but little storage space. Furthermore, when our improved chair is unfolded and drawn up to a table, its appearance, because of the

back and rear leg unit construction, so closely resembles the ordinary type of dining room chair as to hardly to distinguishable therefrom.

Of course, many changes may be made by 60 way of detail without departing from the spirit and scope of our invention. We do not limit ourselves therefore to the exact structure shown and described herein other than by the appended claims. 65

We claim:—

1. A folding chair comprising a frame constituting the rear legs and back, a seat pivoted to said frame, and front legs supporting said seat and having direct pivotal 70 and guided sliding connection with said frame and foldable therewithin.

2. A folding chair comprising a frame constituting the rear legs and back, a seat pivoted to said frame, front legs having 75 direct pivotal and guided sliding connection at their upper ends with said frame and foldable therewithin, and means connecting said front legs and supporting said seat.

3. A folding chair comprising a frame 80 constituting the rear legs and back, a seat pivoted to said frame, front legs having direct pivotal and guided sliding connection at their upper ends with said frame and foldable therewithin, said connection comprising slots in said legs and pins in said 85 frame engaging in said slots, and means on said front legs for supporting said seat.

4. A folding chair comprising a frame constituting the rear legs and back, a seat 90 pivoted to said frame, front legs having direct pivotal and guided sliding connection at their upper ends with said frame and foldable therewithin, said connection comprising slots in said legs and pins in said 95 frame engaging in said slots, and means on said front legs for supporting said seat, said means comprising a connection between said front legs to which said seat is pivotally secured. 100

5. A folding chair comprising a frame constituting the rear legs and back, front legs having direct pivotal and guided sliding connection with said frame and foldable therewithin, and a seat pivoted at its rear edge to said frame and intermediate its rear and front edges to said front legs. 105
